[57] CLAIM

The ornamental design for a handle for a door, as shown and described.

DESCRIPTION

FIG. 1 is a perspective view of a handle for a door showing our new design;

FIG. 2 is a front elevational view thereof;

FIG. 3 is a top plan view thereof;

FIG. 4 is a bottom plan view thereof;

FIG. 5 is a right side elevational view thereof, the left side being a mirror image;

FIG. 6 is a rear elevational view thereof;

FIG. 7 is perspective view of a second embodiment of the design of FIG. 1;

FIG. 8 is a front elevational view of FIG. 7;

FIG. 9 is a top plan view of FIG. 7;

FIG. 10 is a bottom plan view of FIG. 7;

FIG. 11 is a right side elevational view of FIG. 7, the left side being a mirror image;

FIG. 12 is a rear elevational view of FIG. 7.

The broken lines showing a rose plate for a handle in FIGS. 1 and 7 are for purposes of illustration only and form no part of the claimed design.
